GASEOUS ELECTRIC DISCHARGE DEVICE

Hendrik Lems, Eindhoven, Netherlands, assignor
to General Electric Company, a corporation of
New York

Application August 12, 1932, Serial No. 628,578
In Germany August 20, 1931

4 Claims. (Cl. 176—122)

The present invention relates to gaseous electric discharge devices generally and more particularly the invention relates to such devices having auxiliary electrodes to facilitate the starting thereof.

A common defect in this type of electric discharge device is that the material of the auxiliary electrodes sputters off during the operation of the device. This sputtered material deposits on the wall of the container to form an opaque coating thereon which reduces the efficiency and the useful operating life of the device.

The object of the present invention is to provide a gaseous electric discharge device having auxiliary electrodes in which sputtering of electrode material does not occur. Another object of the invention is to increase the efficiency and the life of gaseous electric discharge devices of the above type. Still further objects and advantages attaching to the device and to its use and operation will be apparent to those skilled in the art from the following particular description and from the appended claims.

The invention attains its objects by a coating of oxide material on the auxiliary electrodes which prevents the sputtering of material from said auxiliary electrodes to increase the efficiency and the useful operating life of the electric discharge device.

In the drawing accompanying and forming part of this specification two embodiments of the invention are shown, in which

Fig. 1 is a schematic view of one embodiment of the invention and

Fig. 2 is a similar view of another embodiment of the invention.

Referring to Fig. 1 of the drawing the gaseous electric discharge device comprises a container 1 having electrode chambers 2 and electrodes 3 sealed into stems 6 at each end thereof. Said electrodes 3 consist of a coiled metal wire, such as tungsten, coated with an electron emitting material, such as barium oxide, and are adapted to emit electrons when heated. Any other suitable type of thermionic electrode, such as a Pirani electrode, or a Hull electrode, well known in the art, is used when desired. An auxiliary electrode 4 is sealed into each of said stems 6 and extends toward the center of said container 1. Said electrodes 4 are located in the longitudinal axis of said container 1 and are physically connected to each other in the center of said container 1 by a body 5 of insulation material, such as porcelain. Said electrodes 4 consist of zirconium or aluminum wire and the sur-

face thereof is oxidized. Where desired electrolytic means are used to oxidize the surface of said auxiliary electrodes 4.

Said container 1 is filled with a gaseous atmosphere, such as rare gas, common gas, metal vapor, or a mixture of these and is, for example, a mixture of argon and mercury at a pressure of approximately 6 to 8 mm. Where desired, each of said electrodes 4 is connected through an impedance to one of said thermionic electrodes 3, 10 or each of said electrodes 4 is connected to a separate current source.

When current of 110, 220 or 380 volts is applied to the terminals of the device a discharge takes place between the adjacent end parts of said auxiliary electrodes 4 which ionizes the gaseous filling to facilitate the starting of the positive column discharge in the device. The layer of oxide on said electrodes 4 acts as an insulator and prevents the sputtering of material from said auxiliary electrode 4 during the operation of the electric discharge device.

The embodiment of the invention shown in Fig. 2 is similar to that shown in Fig. 1 except except that cold, cylindrical electrodes 8 and 9 are sealed therein, one at each end of the container 7. A thin metal rod 10 is attached to said electrode 8 and extends along the discharge path between said electrodes 8 and 9 up into the region of the said electrode 9. The surface of said rod 10 is oxidized as disclosed in connection with Fig. 1. When current of 110 or 220 volts is applied to the terminals of the device a discharge takes place between said electrode 9 and the end parts of said auxiliary electrode 10 adjacent thereto which ionizes the gaseous filling to facilitate the starting of the positive column discharge in said device. Due to the coating of oxide material on said electrode 10 the sputtering of material from said electrode 10 is entirely prevented.

While I have shown and described and have pointed out in the annexed claims certain novel features of the invention, it will be understood that various omissions, substitutions and changes in the forms and details of the device illustrated and in its use and operation may be made by those skilled in the art without departing from the broad spirit and scope of the invention.

What I claim as new and desire to secure by Letters Patent of the United States is:—

1. An electric discharge device comprising a container, electrodes sealed therein, a gaseous atmosphere therein, at least two of said electrodes being main discharge supporting electrodes, an auxiliary electrode extending from one of said

main electrodes to a point adjacent the other of said main electrodes, said auxiliary electrode being coated with the oxide of the material constituting said auxiliary electrode to prevent sputtering of material from said auxiliary electrode during the operation of said device.

2. An electric discharge device comprising a container, electrodes sealed therein, a gaseous atmosphere therein, at least two of said electrodes being main discharge supporting electrodes, an auxiliary electrode extending from one of said main electrodes to a point adjacent the other of said main electrodes, said auxiliary electrode being a zirconium wire coated with zirconium oxide.

3. An electric discharge device comprising a container, electrodes sealed therein, a gaseous atmosphere therein, at least two of said electrodes being main discharge supporting electrodes, an

auxiliary electrode extending from one of said main electrodes to a point adjacent the other of said main electrodes, said auxiliary electrode being an aluminum wire coated with aluminum oxide.

4. An electric discharge device comprising a container, a gaseous atmosphere therein, electrodes sealed therein, at least two of said electrodes being main discharge supporting electrodes, two other electrodes being elongated electrodes extending from opposite ends of said container toward the center thereof, the adjacent ends of said elongated electrodes being physically joined by a body of insulation material, each of said elongated electrodes being coated with the oxide of the material constituting said elongated electrode and which is non-sputtering during the operation of the device.

HENDRIK LEMS.
